2 SHEETS—SHEET 2.

FIG. 2.

FIG. 3.

UNITED STATES PATENT OFFICE.

WILLIAM A. JOHNSTON, OF PRINCE BAY, NEW YORK, ASSIGNOR TO THE S. S. WHITE DENTAL MANUFACTURING COMPANY, A CORPORATION OF PENNSYLVANIA.

DENTAL-EQUIPMENT STAND.

1,290,568.

Specification of Letters Patent.

Patented Jan. 7, 1919.

Application filed October 14, 1918. Serial No. 258,109.

To all whom it may concern:

Be it known that I, WILLIAM A. JOHNSTON, a citizen of the United States, and a resident of Prince Bay, in the county of 5 Richmond, State of New York, have invented certain new and useful Improvements in Dental-Equipment Stands, of which the following is a specification, reference being had to the accompanying drawings.

My invention relates particularly to stands for supporting various equipments, implements and devices employed by the dentist in the execution of the duties incident to 15 his profession, and is especially directed to the convenient position of the electrical mechanism.

The principal object of my invention is to provide an equipment stand arranged to 20 be placed in convenient proximity to a dental operating chair, and in which the spittoon carrying pedestal serves as a conduit through which air, gas and electric current may be supplied to the accessory devices 25 employed, as well as the water for said spittoon and its tumbler.

Other objects of my invention are to provide an equipment stand with the controlling parts and implements so conveniently 30 arranged as to be within easy reach from the operator's position and to afford free and convenient access of the operator to said parts and implements without interfering with the use of the spittoon by the patient.

Specifically stated, the form of my invention as hereinafter described, comprehends an equipment stand comprising a spittoon-supporting pedestal having in its base a chamber providing a distributing station 40 wherein the electrical connections for the various devices employed may be made with the line circuit, and having a hollow arm projecting laterally and upwardly and carrying an accessory head embodying a 45 switchboard, from where the various devices may be controlled.

My invention also includes all of the various novel features of construction and arrangement as hereinafter more definitely 50 specified.

In the accompanying drawings, Figure 1 is a sectional elevational view showing a spittoon pedestal carrying an accessory head, embodying a switchboard in accordance with my invention; Fig. 2 is a plan

sectional view of said pedestal taken on the line 2—2 in Fig. 1; and Fig. 3 is a sectional elevational view of the accessory head showing the contact plate of the switchboard and the air and gas controlling mechanism in 60 elevation for convenience of illustration.

In said figures the pedestal 1 has the base 2 and supports the spittoon bowl 3 and the tumbler-holder 5 carrying the tumbler 6, being supplied with water through the water 65 supply pipe 7 which is connected with the distributing pipe 9 by the conduit 10, controlled by the valve 11 having the handle 12. The waste water discharged from the spittoon bowl and tumbler-holder is carried 70 through the pedestal by the waste-pipe 13 which is connected by the union 15 with the drain pipe 16 leading to the sewer or other suitable outlet.

The pedestal 1 is provided with the laterally and upwardly extending hollow arm 17 which conveniently supports the accessory head 19 embodying the switchboard 20, and comprising air controlled valves 21 and 22, and their respective pressure indicators 23 80 and 24, and the electric current regulators or rheostats 25, 26 and 27, whose handles 28, 29 and 30, respectively, carry indicating pointers arranged to indicate by the graduations of the respective dials 31, 32 and 33, 85 the position of the contact engaging arms 35, 36 and 37, respectively, which swing over and engage the contacts 39, 40 and 41, of the rheostats 25, 26 and 27 respectively.

The accessory head 19 conveniently carries the engine 43 comprising the motor 45 and handpiece 46; the spray bottle holder 47 comprising the spray bottles 48 and 49 and tumbler 50; the spot lamp 51 which is connected by universal joints 52 and 53 and 90 the link 54 with the arm 55 and standard 56; the bracket table 57 pivotally supported by the bracket arm 58 and link 59; and the signal lamp 60 which may be connected to flash desired signals to the operator. The spot 100 light 51 is preferably composed of suitably disposed lenses and reflector adapted to direct intensified rays of light into the patient's mouth, and is supported by the bracket having universal joints so that it 105 may be positioned to direct rays of light at any desired angle.

Said accessory head is provided with air outlets respectively controlled by their valves 62, 63 and 64, to the nipples of which 110

the various air actuated implements are connected; the chip blower 65 being connected by the flexible tubing 66 with the outlet having the valve 62; the spray bottle valve 69 being connected by the flexible tubing 70 with the outlet having the valve 63; and the hot air syringe 71 being connected by the flexible tubing 72 with the outlet having the valve 64.

10 As clearly shown in Fig. 1, the chip blower 65, spray bottle valve 69 and the hot air syringe 71 may be respectively supported when not in use upon the hooks 73, 74 and 75 projecting from the bracket arm 58.

15 The switchboard 20 is provided with plug sockets 76, 77 and 78 for the reception of the terminal plugs 79, 80 and 81; the plug 79 being connected by the flexible cord 82 with the mouth lamp 83; the plug 80 being connected by the flexible cord 85 with the cautery 86 or other such instrument; and the plug 81 being connected by the flexible cord 88 with a suitable heating coil 89 in the flexible tubing 72 for heating the air for the 25 syringe 71.

The bracket table 57 is provided with the gas burner 90 which is connected by the flexible tubing 91 with the nipple 92 of the gas controlling valve 93 in the pipe 94 which 30 leads through the accessory head 19, arm 17 and pedestal 1, and which is arranged to be connected through the base 2 with any suitable source of gas supplied by the union 95.

35 The compressed air for the chip blower 65, spray bottle valve 69 and hot air syringe 71 is filtered through the filter 96 in the accessory head 19, see Fig. 3, to which it is carried by the air pipe 97 leading through the 40 arm 17 and pedestal 1, and having the union 98 by which it is arranged to be connected through the base 2 with any suitable source of air supply.

The electrically operated devices are connected to the switchboard by the leads 99 forming a cable which extends through the arm 17 and pedestal 1 to a suitable distributing station comprising the box 100, in the base 2 of the pedestal 1. As shown in Figs. 50 1 and 2, a sheath or conduit is provided to protect the cable from any moisture incident to drip or condensation on the pipes passing through the pedestal 1.

The motor 45 of the engine 43 is arranged 55 to be controlled by the foot controller 102 having the pedal lever 103 and connected by the flexible cord 105 with the leads 106 and 107 of the motor 45 at the distributing station above described.

60 It will be obvious that by supporting the accessory head comprising the switchboard on the spittoon pedestal, great convenience to the operator is afforded, and a consequent saving of time effected as well as conserving 65 valuable floor space.

I do not desire to limit my invention to the precise details of construction and arrangement as herein set forth as it is obvious that various modifications may be made therein without departing from the essential features of my invention as defined in the appended claims.

Having thus described my invention, I claim:

1. A dental equipment stand comprising 75 a spittoon and an accessory head embodying a switchboard, supported by a pedestal having a base, an electrical distributing station in said base, connections from said station through said pedestal to said switchboard, a plurality of instruments connected with said switchboard, and means on said accessory head arranged to selectively control said instruments.

2. A dental equipment stand comprising 85 a pedestal having a base, a spittoon supported by said pedestal, and having supply and waste pipe connections extending therethrough, a hollow arm extending laterally and upwardly from said pedestal, an accessory head embodying a switchboard supported by said arm, connections extending through said pedestal and arm for carrying air and gas to said accessory head, and electrical connections extending through said 95 pedestal and arm arranged to supply electric current to said switchboard.

3. A dental equipment stand comprising 100 a pedestal, a spittoon supported by said pedestal and having supply and waste pipe connections extending therethrough, a hollow arm extending laterally and upwardly from said pedestal, an accessory head embodying a switchboard supported by said arm, and carrying a dental engine having a motor, a 105 spray bottle holder and spotlight, and having connected therewith a plurality of electrically operated implements, and controlling means on said switchboard for controlling the actuation of said electrically operated implements.

4. A dental equipment stand comprising a pedestal having a base, a spittoon supported by said pedestal and having supply and waste pipe connections extending therethrough, a hollow arm extending from said pedestal, an accessory head embodying a switchboard supported by said arm, and carrying a dental engine comprising a motor, a spray bottle holder, a spotlight and bracket 115 table, and carrying a plurality of air, gas and electrically operated implements, and controlling means on said accessory head for controlling the various devices carried thereby, and air, gas and electric conduits leading through said pedestal from said accessory head, and an electrical distributing station disposed in said base.

5. A dental equipment stand comprising 120 a pedestal having a base, a spittoon sup-

ported by said pedestal and having supply and waste pipe connections extending therethrough, an electrical distributing station in said base, a hollow arm extending from 5 said pedestal, an accessory head embodying a switchboard supported by said arm and carrying a dental engine comprising a motor, a spray bottle holder, a spotlight, and a jointed bracket table, a gas burner on said 10 table, connected with said accessory head, a plurality of air and electrically operated implements connected with said accessory head, air, gas and electrical conduits leading through said pedestal to said accessory head, a distributing station in said base, and controlling means on said accessory head for controlling the various implements. 15

In testimony whereof, I have hereunto set my hand this 8th day of October, A. D., 1918.

WILLIAM A. JOHNSTON.
